COMBINED ASH TRAY, TOBACCO HUMIDOR, PIPE RACK AND STAND

Arnold Goldstein, Allentown, Pa., assignor to
Keystone Lamp Mfg. Corp., Slatington, Pa., a
corporation of Pennsylvania

Application May 5, 1949, Serial No. 2,448
Term of patent 7 years

(Cl. D85—2)

To all whom it may concern:

Be it known that I, Arnold Goldstein, a citizen of the United States of America, residing in the town of Allentown, county of Lehigh and State of Pennsylvania, have invented a new, original, and ornamental Design for a Combined Ash Tray, Tobacco Humidor, Pipe Rack and Stand, of which the following is a specification, reference being had to the accompanying drawing, forming part thereof:

Figure 1 is a front elevational view of a combined ash tray, tobacco humidor, pipe rack and stand showing my new design.

Figure 2 is a side elevational view of the combined ash tray, tobacco humidor, pipe rack and stand shown in Figure 1, the stand portion fragmentarily shown for convenience of illustration.

Figure 3 is a plan view of a combined ash tray, tobacco humidor, pipe rack and stand of Figure 1.

Figure 4 is a fragmentary sectional view of a combined ash tray, tobacco humidor, pipe rack and stand as seen from the plane 4—4 on Figure 1.

The dominant features of my design reside in those portions shown in full lines.

I claim:

The ornamental design for a combined ash tray, tobacco humidor, pipe rack and stand, as shown and described.

ARNOLD GOLDSTEIN.
